UNITED STATES PATENT OFFICE.

FOREST V. DETWILER, OF CHICAGO, ILLINOIS.

HYDROCARBON-BURNER.

1,239,775.

Specification of Letters Patent. Patented Sept. 11, 1917.

Application filed April 8, 1914. Serial No. 830,340.

To all whom it may concern:

Be it known that I, FOREST V. DETWILER, a citizen of the United States, residing at Chicago, in the county of Cook and State 5 of Illinois, have invented certain new and useful Improvements in Hydrocarbon-Burners, of which the following is a specification.

This invention relates to improvements in 10 hydro carbon burners, particularly adapted, though not necessarily limited in its use for burning kerosene, and one of the objects of the same is to provide a burner of this type, which will be simple, durable and compact 15 in construction, and effective and efficient in operation, and one which will economically burn kerosene with a blue flame which gives no odor.

To the attainment of these ends and the 20 accomplishment of other new and useful objects as will appear, the invention consists in the features of novelty, in substantially the construction, combination and arrangement of the several parts, hereinafter 25 more fully described and claimed, and shown in the accompanying drawings illustrating the invention, and in which—

Figure 1 is a vertical longitudinal sectional view of an improved burner of this 30 type constructed in accordance with the principles of this invention.

Fig. 2 is a top plan view of the parts of the burner shown in Fig. 1.

Fig. 3 is a sectional view as taken on line 35 3—3, Fig. 1.

Fig. 4 is a detail view, partly in elevation and partly in section of the tube for lighting the burner.

Fig. 5 is a top plan view of the initial 40 heating or what is sometimes called the priming cup.

Fig. 6 is a view partly in elevation and partly in vertical longitudinal section, of a modified form of the burner.

Fig. 7 is a top plan view of the parts shown in Fig. 6.

Referring more particularly to the drawings, the numeral 10 designates generally a vaporizing chamber which is preferably circular in cross section and is of a width somewhat greater than the height thereof, so as to form a flattened chamber. This chamber is preferably annular in construction to form an opening of some size through the 55 center thereof, and which opening is out of communication with the chamber. Encom-

passing the opening thus formed is a wall, the portion 11 of which projects on one side of the chamber in the form of an annular flange, and the portion 12 projects on the 60 opposite side of the chamber, and depends for some distance below the lower face of the chamber. This flange 12 is provided with a series of lateral openings projecting therethrough adjacent the lower face of the 65 chamber 10, and the chamber 10 is preferably reduced in size as at 14 to form a pocket 15 surrounding the flange 12 and in which pocket the flame enters as it passes through the openings 13, so as to impinge 70 on the bottom of the chamber to heat the latter. These flanges 11 and 12 forming a wall around the opening may be of any desired length, and the upper portion of the wall thus formed is flared outwardly as at 75 16 for a purpose to be hereinafter described. The kerosene is supplied to the chamber 10 through the inlet opening 17 by means of a pipe 18 which leads from a tank 19, located in such position with respect to the 80 chamber 10 that the oil will be fed by gravity to the chamber 10. A controlling valve 20 is provided in the pipe 18 for controlling the supply of oil to the chamber.

Arranged within the wall formed by the 85 flanges 11, 12 is another chamber 21, which is of a size somewhat smaller than the diameter of the opening to form a flame passage 22 between the wall of the chamber 21 and the wall surrounding the opening. This 90 chamber 21 is provided preferably with a flange 23 projecting thereabove, and which flange preferably extends above the flange portion 11 of the wall, and is itself flared outwardly from the chamber 21, to coöperate 95 with the flared portion 16 to direct the flame away from the chamber 21, and to spread the flame. The chamber 21 is preferably held in position by means of a pipe 24 which is connected with the chamber 21 to communicate therewith and forms an inlet for the vapor from the chamber 10 into the chamber 21, this pipe 24 being also connected to the outlet 25 of the chamber 10.

Leading from the chamber 21 is an outlet pipe 27, which conducts the vapor from the chamber 21 to a pipe 27 which is arranged below both of the chambers, to extend transversely with respect to the opening in the chamber 10, which is surrounded 110 by the wall, and this pipe 27 is provided with a jet opening 28 arranged directly be-

low the bottom 29 of the chamber 21 so as to direct the flame into the space surrounded by the flange portion 12 of the wall and against the bottom of the chamber 21. This 5 bottom 29 of the chamber is preferably arched or curved upwardly as shown and stands above the openings 13 in the wall surrounding the opening in the chamber 10, and serves as a means for directing the im- 10 pinging flame through the openings 13 so that the flame will strike the bottom of the chamber 10. At the same time a portion of the flame will pass through the flame passage 22 to encompass the chamber 21, heat- 15 ing the latter to a high temperature, and the flame will also be directed to portions of the pipes 24, 26.

In order to assist in further heating the pipe 26, the latter may if desired be ar- 20 ranged so that it will pass through a portion of the chamber 10, and a controlling valve 31 is arranged in the pipe 26 for con- trolling the supply of vapor to the jet opening 28.

25 Thus it will be manifest that when the vapor which is fed through the jet 28, is ignited, the flame will act directly upon the chamber 21 to heat the latter, a portion of the flame being directed through the open- 30 ings 13 to heat the chamber 10, while another portion will pass through the passage 22 entirely encompassing the chamber 21. The liquid being cooled as it is fed into the chamber and discharged at a higher tem- 35 perature prevents the formation of carbon in the vapor generator, due to the high tem- perature which is obtained, and when the vapor flows from the chamber 10 into the chamber 21, it will be heated to a very high 40 degree, and the super heating of the pipes 24, 26 prevents any possible condensation, so that the vapor will be discharged in a perfectly dry condition through the jet opening 28. By the aid of this super heat- 45 ing and a supply of sufficient air a blue flame is produced which has no odor.

In order to facilitate the formation of the chambers 10 and 21, the former is pro- 50 vided with plug openings 32 which may be closed by suitable plugs 33 and the chamber 21 is provided with plug openings which may be closed by suitable plugs 34. The burner thus formed is adapted for any stoves, either for large or small stoves, or 55 for boiler or furnace use and may be sup- ported in any desired manner preferably by means of a supporting frame or construction of any desired configuration, the frame preferably being formed of angle pieces 35 60 having walls 36 secured thereto and a closed bottom 37. The top 38 of the construction is provided with an opening 39 of such a size that when the chamber 10 rests upon the top 38, the projecting flange 12 which 65 forms a portion of the wall will extend into

the supporting structure and the pipe 27 will also extend into the interior of the structure, preferably by passing through a suitable opening in one of the walls in the structure. In order that the valve device 70 31 which controls the supply of vapor to the jet opening 28 may be manipulated from the front, it is provided with a long handle which extends toward the front of the structure and preferably terminates in close 75 proximity to the valve device 20.

In order that the supply of air to the jet opening, which is necessary to support com- bustion, may be controlled, some of the walls 80 36 of the supporting device, are provided with air openings or passages 40 and a closure 41 which is itself provided with apertures adapted to be brought into and out of register with the openings 40, is pro- 85 vided for each series of these openings and may be manipulated by means of handles 42 connected therewith.

To initially heat the vaporizing chamber 10 and the chamber 21 to start the burner, there is provided an initial heating device 90 or what is sometimes called a priming cup, which is preferably in the shape of a tray 43 having concentric chambers 44—45 spaced from each other to form an air passage of some size therebetween and which air pas- 95 sage encompasses the chamber 45. The chambers are connected preferably by means of ribs 47 extending across the air passage 46 and these ribs are provided with pas- sages or openings 48 which form communi- 100 cation between the chambers 44, 45 so that when the supply of oil is fed to the cham- ber 45 it will flow through the passages 48 and into the chamber 44. The chamber 45 is preferably provided at its center with an 105 opening 49 of some size through the bottom thereof and a depending and outwardly flared flange is preferably provided and ex- tends below the bottom of the chamber 45. An upwardly projecting flared flange 51 also 110 surrounds the opening 49 and is preferably of a length to extend above the top of the chamber 45. This flange 51 is preferably provided with lateral openings 52 there- 115 through which form air passages and these openings 52 are arranged in alinement with similar openings 53 in the walls of the cham- bers 44, 45. Arranged within the chambers and below these openings is asbestos 54 and tubular members 55 are secured to and ex- 120 tend through the bottoms of the chambers 44, 45 to form air passages, and the upper extremities of these tubular members are preferably flared as at 56. The chambers 44, 45 are of such a size and are so arranged 125 that the chamber 45 will be disposed below the chamber 21 while the chamber 44 will stand below the chamber 10 to heat the lat- ter, and in such a position that when the oil in the chamber 44 is ignited the flame will 130

impinge on the chamber 10 outside of the flange portion 12 of the wall which extends downwardly from the chamber 10 and enters the flame pocket 15.

5 The chamber 45 is supplied with oil from the jet opening 28 and in order to prevent the oil from dropping through the opening 49 in the bottom of the chamber 45, a shield 57 is provided which may be adjustably supported by the pipe 27 above the opening 49 so that the oil will be deposited on the shield and will flow therefrom into the chamber 45. This initial heating device or priming cup may be removably supported in any manner, 15 but preferably by means of hangers 58 in the form of hooks which are of a size and shape to hook over ears or projections 59, which are provided therefor and are preferably arranged in the flange portion 12 of 20 the wall 11, 12. This device is also housed within the supporting structure, and the opening 39 in the top 38 of the structure is of such a size that it will permit this device to be passed into the housing when the chamber 10 is placed in position to rest upon the 25 top of the structure.

After the chambers 44, 45 have been supplied with oil, the oil may be ignited in any suitable manner, preferably by means of a 30 tube 60 having a handle 61 and a series of apertures 62, the latter being arranged in one end, and suitable material 63 is arranged in the tube adjacent the apertures for holding oil, so that when the end of the tube is 35 immersed in oil, the oil may be ignited when the tube is withdrawn, and the lighter end of the tube may be passed through a suitable opening in one of the walls of the supporting structure to ignite the oil in the chambers 44, 45.

40 In the form of the invention shown in Figs. 6 and 7, the chamber 21 is dispensed with, and in lieu thereof there is provided a chamber 64, which is formed at the junction of two pipes 65, 66, which latter lead from outlet openings 67, 68 of the chamber 10, the outlets being preferably opposite each other, so that the pipes 65, 66 will be in alinement and the chamber 64 will be disposed in alinement with the opening formed 45 through the chamber 10 and slightly above the top of the wall formed by the flange portions 11, 12. In this form of the invention, the liquid will pass into the chamber 10 50 through the pipe 69 which leads from the supply tank and is controlled by a valve 70. The oil after being heated in the chamber 10 will pass out of the openings 67, 68 into the pipes 65, 66 to be discharged into the 55 chamber 64. From this chamber 64 the vapor will flow through a pipe 71, and which latter pipe preferably passes through the chamber 10 similar to the manner in which the pipe 26 passes therethrough. A pipe 72 60 similar to the pipe 27, is connected with the

65 pipe 71 and the jet opening 73 in the pipe 72 is arranged in a manner similar to the jet opening in the pipe 27.

Arranged above the jet opening 73 and preferably within the opening surrounded 70 by the wall formed by the flanges 11, 12 is a deflector and spreader 7 which is arched or deflected upwardly as shown, and is of a size somewhat less than the size of the opening in which it is arranged. This deflector 75 is adjustably supported preferably by means of a stem 75 having threads thereon and which stem passes through a threaded core 76 of the chamber 64. Thus it will be manifest that the deflector and spreader 74 may 80 be adjusted toward and away from the jet opening 73 for controlling the flame and for producing the desired kind of a flame. The device is so constructed that when it is adjusted to stand approximately two and one 85 half inches from the jet opening 73 a yellow flame will be produced. A distance of approximately one and three fourths inches therefrom will produce a white flame while the deflector and spreader when positioned 90 approximately one and one fourth inches from the jet opening will result in the production of a blue flame which will burn without odor.

95 By the provision of the particular form of heating device or priming cup, the chambers may be more readily heated and quicker results may be obtained, and by the provision of the second heating chamber into which the vapor is discharged and again heated, 100 the temperature is raised to a very high degree and complete vaporization results, and by the arrangements of the pipes which form the conduits or passages through which the vapor flows, in such positions that they 105 will also be impinged upon and heated by the flame, all possibility of condensation is avoided.

What is claimed as new is:—

1. A burner of the character described 110 embodying an annular vaporizing chamber having a fluid inlet and a vapor outlet, a perpendicular flange encompassing the opening and projecting beyond opposite faces of the chamber, said flange having openings 115 therethrough to direct the flame against one wall of the chamber, a second chamber disposed in alinement with the opening and within the plane of the periphery of the flange, said second chamber having an inlet 120 connected with the outlet of the first said chamber, and a jet opening connected with the second recited chamber and disposed in alinement with the said opening and below both of the chambers. 125

2. A burner of the character described 130 embodying a chamber having an opening of some size therethrough and out of communication therewith, the wall of the opening projecting beyond the chamber, said

bers, the last recited provisions embodying a priming receptacle removably supported below the chambers.

9. A burner of the character described embodying a vaporizing chamber to which the oil flows, and a superheating chamber to which the vapor flows from the vaporizing chamber, a burner proper for heating the chambers, and means for initially heating the chambers, the said means embodying a priming receptacle having separate chambers having communication, whereby fuel may flow from one to the other chamber, each of the chambers of the priming receptacle being disposed to heat one of the first recited chambers.

10. A burner of the character described embodying a plurality of heating chambers, a burner proper for heating them, and an initial heating device for the chambers, said device embodying two chambers, each of which is arranged to heat one of the first recited chambers, one of the chambers of the said device encompassing and being spaced from the other chamber to form an air passage therebetween encompassing the innermost chamber and air passages extending through the bottoms of each chamber.

11. A burner of the character described embodying a plurality of heating chambers, a burner proper for heating them, and an initial heating device for the chambers, said device embodying two chambers, each of which is arranged to heat one of the first recited chambers, one of the chambers of the said device encompassing and being spaced from the other chamber to form an air passage therebetween, there being oil passages leading from one to the other of the chambers of said device, there being also air passages through each of the chambers in the said device.

12. A burner of the character described embodying a plurality of heating chambers, a burner proper for heating them, an initial heating device for the chambers, said device embodying two chambers, each of which is arranged to heat one of the first recited chambers, one of the chambers of the said device encompassing and being spaced from the other chamber to form an air passage therebetween, provisions for conducting oil from one to the other of the chambers in said device, and upright tubular members arranged in each of the last said chambers and passing through the bottom of the chambers to form air passages therethrough.

13. A burner of the character described embodying a vaporizing chamber having an opening of some size therethrough and closed to the chamber, a wall surrounding the opening, and projecting on opposite sides of the chamber to form a passage of some length, said wall having lateral openings therethrough, beneath and in close

proximity to the lower wall of the chamber, a second chamber arranged within the wall above the said openings, the wall of the second chamber being spaced from and cooperating with the first said wall to form a flame passage, the vapor chamber having a supply inlet and an outlet, provision for conducting the vapor from the first to the second chamber, a burner proper arranged below the chamber, and provision for connecting the burner with the second recited chamber.

14. A burner of the character described embodying a vaporizing chamber having an opening of some size therethrough and closed to the chamber, a wall surrounding the opening, and projecting on opposite sides of the chamber to form a passage of some length, said wall having lateral openings therethrough, beneath and in close proximity to the lower wall of the chamber, a second chamber arranged within the wall above the said openings, the wall of the second chamber being spaced from and cooperating with the first said wall to form a flame passage, the vapor chamber having a supply inlet and an outlet, provisions for conducting the vapor from the first to the second chamber, a burner proper arranged below the chamber, and a pipe leading from the second said chamber to the burner, said pipe passing through the first said chamber.

15. A burner of the character described embodying a vaporizing chamber having an opening of some size therethrough and closed to the chamber, a wall surrounding the opening, and projecting on opposite sides of the chamber to form a passage of some length, said wall having lateral openings therethrough, beneath and in close proximity to the lower wall of the chamber, a second chamber arranged within the wall above the said openings, the wall of the second chamber being spaced from and cooperating with the first said wall to form a flame passage, the vapor chamber having a supply inlet and an outlet, provisions for conducting the vapor from the first to the second chamber, a burner proper arranged below the chamber, and provisions for conducting vapor from the top of the second said chamber across the said flame space and to the burner, through the first said chamber and without discharging into the first said chamber.

16. A burner of the character described embodying an oil heating chamber and a heating chamber for the vapor, means for conducting the oil from one to the other of the chambers, means for supplying one of the chambers with fuel to be vaporized, a burner proper, arranged below the chambers, means for supplying the burner with vapor from one of the chambers, a supporting structure having closed sides and base, and

provided with a top having an opening to receive and inclose the burner proper, there being air openings through the walls of the supporting structure, and means for varying the size of such openings.

17. A burner of the character described embodying an oil heating chamber and a heating chamber for the vapor, means for conducting the vapor from one to the other 10 of the chambers, means for supplying one of the chambers with fuel to be vaporized, a burner proper, arranged below the chambers, means for supplying the burner with vapor from one of the chambers, a supporting structure having closed sides and base, 15

and provided with a top having an opening to receive and inclose the burner proper, there being air openings through the walls of the supporting structure, means for varying the size of such openings, and provisions 20 for controlling the burner proper from the outside of the supporting structure.

In testimony whereof I have signed my name to this specification, in the presence of two subscribing witnesses, on this 3rd day 25 of April, A. D. 1914.
